Joseph W. Snavely, Hales Corners, Wis., assignor to
Chain Belt Company, Milwaukee, Wis., a corporation
of Wisconsin

Filed Nov. 9, 1959, Ser. No. 58,280

Term of patent 14 years

(Cl. D55—1)

FIG. 1.

FIG. 2.

FIG. 3.

FIG. 4.

FIG. 1 is a perspective view of a combined belt conveyor span and pedestals, showing my new design. The sections of the conveyor belt shown on the span in broken lines are for illustrative purposes only.

FIG. 2 is a cross-section of the conveyor span, taken on the line 2—2 of FIG. 4, with the pedestal shown in elevation.

FIG. 3 is a plan view of the combined belt conveyor span and pedestals; and

FIG. 4 is a side elevation of the combined belt conveyor span and pedestals.

I claim:
The ornamental design for a combined belt conveyor span and pedestals, substantially as shown and described.
